US0D1070501S

(12) **United States Design Patent** (10) **Patent No.:** **US D1,070,501 S**
(45) **Date of Patent:** **** Apr. 15, 2025**

(54) **WATER BOTTLE**

(71) Applicants: **Leso Rocity (Shenzhen) Industrial Co., Ltd**, Guangdong (CN); **Shenzhen Rongcheng Innovation Technology Co., LTD**, Guangdong (CN)

(72) Inventors: **Weijun Xiao**, Shenzhen (CN); **Fangjian Zhang**, Shenzhen (CN)

(73) Assignees: **LesoRocity (Shenzhen) Industrial Co., Ltd**, Shenzhen (CN); **Shenzhen Rongcheng Innovation Technology Co., LTD**, Shenzhen (CN)

(**) Term: **15 Years**

(21) Appl. No.: **29/891,395**

(22) Filed: **May 5, 2023**

Related U.S. Application Data

(63) Continuation of application No. 17/969,598, filed on Oct. 19, 2022, which is a continuation-in-part of application No. 17/020,807, filed on Sep. 15, 2020, now Pat. No. 11,653,625, which is a continuation-in-part of application No. 16/550,269, filed on Aug. 25, 2019, now Pat. No. 11,304,404.

(57) **CLAIM**

The ornamental design for a water bottle as shown and described.

DESCRIPTION

FIG. 1 is a perspective view of the water bottle showing our new design;

FIG. 2 is another perspective view thereof;

FIG. 3 is a front view thereof;

FIG. 4 is a rear view thereof;

FIG. 5 is a left view thereof;

FIG. 6 is a right view thereof;

FIG. 7 is a top view thereof; and,

FIG. 8 is a bottom view thereof.

The broken lines show portions of the water bottle that form no part of the claimed design.

1 Claim, 7 Drawing Sheets
